EDGE-TURNING MACHINE

Herbert J. Heller, New York, N. Y., assignor to
 H. Weiss & Company, New York, N. Y., a co-
 partnership

Application June 16, 1936, Serial No. 85,453

5 Claims. (Cl. 153—29)

My invention relates to machines for shaping sheet metal and pertains particularly to such machines as are used for turning edges to form flanges on sheet metal plates.

5 One of the objects of my invention comprises producing an edge-turning machine which is simple and inexpensive yet fully effective and efficient for all classes of work for which such machines are employed.

10 Another object comprises producing an edge-turning machine by means of which a flange may be turned in small reentrant openings, reentrant apertures having small openings thereto, or apertures of small diameter located wholly within the 15 area of sheet metal plates whether such plates are large or small.

15 A further object comprises producing an edge-turning machine employing a forming element which may be adjusted for optimum operative position and to compensate for wear thereof.

20 A still further object comprises producing an edge turning machine having a forming element of substantially uniform cross-section substantially encircling one of the rolls to ensure longevity for the element.

25 I accomplish all of the above noted desirable results and others which will hereinafter be apparent by means of the novel structure, combination, inter-relation and arrangement of parts 30 which will be hereinafter more specifically described with reference to the accompanying drawings forming a part of this specification and in which like numerals designate corresponding parts throughout.

35 In the accompanying drawings:

Fig. 1 is a partially broken, sectional elevation of one embodiment of my invention;

Fig. 2 is a broken, sectional view of the same taken on the line 2—2 of Fig. 1;

40 Fig. 3 is a partially broken top plan view of the same; and

Fig. 4 is a partially broken, sectional plane view of the same taken on the line 4—4 of Fig. 1.

45 Referring now to the drawings in which I have illustrated one embodiment of my device, and particularly to Figs. 1, 2 and 3. The housing 1 is preferably cast of metal in the form shown and provided with a top or cover 2 secured thereto by machine screws, as shown. A boss in the 50 housing 1 serves as a journal for a hollow shaft 3, one extremity of which bears a spur gear 4 and a bevel gear 5. A stub shaft 8 is provided with a spur gear 9 in mesh with spur gear 4 and shaft 8 is carried in a journal 6 which is carried in turn by means of a U-shape yoke 12 ro-

tatably supported by shaft 13 supported by the housing 1. The lower extremity 14 of journal 6 is given a rectangular form as shown and the journal and shaft carried thereby are adjustable by means of a screw 10 carried in the housing 1. A spring 11, one extremity of which is secured to the yoke 12 and the other to the housing 1, serves to hold the rectangular portion 14 of the journal at all times against the end of the adjusting screw 10. The purpose of this adjustment will 10 be explained hereinafter.

A cross-shaft 17 is journaled in a boss provided in the housing 1 and carries a bevel gear 16 in mesh with bevel gear 5 carried by hollow shaft 3. These bevel gears have preferably 15 a ratio of 1—1 and the shafts 3 and 8 may be rotated by means of a handle, not shown, secured to the extremity of cross-shaft 17. If desired, shafts 3 and 8 may be rotated through a reducing gearing by means of the shaft 18, journaled in the housing 1, and the spur gears 19 and 20. These as shown provide a gear reduction to facilitate rotating shafts 3 and 8 by means of handle 31. The extremities of shafts 3 and 8 are provided with taper flutings or corrugations as 20 indicated and forming rollers 21 and 22 are forced thereon respectively in a manner to ensure that the rollers will not turn on the shafts. The rollers 21 and 22 are, as shown, knurled and provided with reverse tapers so that the flange formed 25 thereby will be substantially perpendicular to the plane of the sheet of metal in which the flange is made. The rolls are adjustable in their distance from each other to accommodate different thicknesses of metal being flanged by 30 means of the screw 10 whereby the journal 6 and shaft 8 may be adjusted with respect to hollow shaft 3 which may be considered a driving shaft with respect to stub shaft 8. A gauge 24 is adjustable by means of the right and left hand threaded screws 29 and 30 carried by the housing 1 to predetermine the height of the flange being 35 formed.

A support rod 28 extends through the hollow driving shaft 3 and is rigidly secured as shown 45 in the top plate 2 of the housing 1. A work table 25 is adjustably secured by means of set screw 27 to the extended portion of the support rod 28. The work table carries a clamp 26 by means of which the machine may be secured to a work bench.

An annular forming element 23 substantially 50 encircles roll 21 as shown in Fig. 4 and an extremity 32 of this element, is operatively positioned with respect to the periphery of the rolls 55

21 and 22 to cooperate therewith in producing the flange as hereinafter described. The forming element 23 is preferably made of high grade tool steel and is rigidly secured in a recess in the work table 25 in any well known manner such as by heat shrinking. The forming element 23 is provided with the proper contour for the purpose intended and the contour is uniform throughout the entire length of the element. Therefore, as the forming edge 32 of the element wears, the work table 25 carrying the forming element may be rotated on the rod 28 to maintain the optimum operative position for the forming edge 32. Of course, the housing 1 carrying the rod 28 may, if desired, be rotated to accomplish the same purpose. Further, the relative rotation between the rod 28 and the work table 25 may be utilized to adjust the forming edge 32 of the forming element 23 to optimum operative position for different kinds or thicknesses of metal.

It will be obvious that, as the cross-section of the element 23 is uniform throughout, longevity of the element is achieved and, further, that the forming edge 32 may be adjusted to compensate for wear or for optimum operative position for different thicknesses or different kinds of material being operated on.

It will be further obvious that as the support rod 28 is the only connecting medium between the housing 1 and the work table, that reentrant apertures in metal sheets having openings thereto only slightly larger than the diameter of the support rod 28 may be easily flanged. Further, that the work table 25 may be removed and the support rod 28 inserted in openings only slightly larger in diameter than the forming element 23 when such openings are located within the area of large or small metal sheets or in apertures having smaller openings thereto than the diameter of the rod 28 to permit flanges to be turned in such small completely enclosed openings or reentrant apertures having small openings thereto.

45 In operating the machine, the edge of the metal to be flanged may be, if desired, turned up for a portion thereof at the flange point that the rolls may more readily obtain a grip thereon and is then fed between the rolls from the side 50 of the machine shown in Fig. 1. The distance between the rolls is adjusted, as hereinbefore described, so that the metal is tightly gripped between them and the height gauge is set for the height of flange desired. The rolls are rotated 55 in a direction to draw the edge of the sheet against the forming edge 32 of the forming element 23 which functions to upturn a portion of the sheet for passage between the rolls to produce the desired flange. The rolls may be rotated either through the reducing gears by means of handle 31 and shaft 18, or directly by means of a handle placed on shaft 11. The flange may also be started if the metal is not too thick without turning up a portion thereof 60 as just described, as the contour of the edge 32 of the forming element is such as to curl the edge of the metal sheet forced against it to a height sufficient for the rolls to obtain an initial grip thereon.

70 It will be apparent from the foregoing that my invention provides an edge-turning machine which is simple and inexpensive yet fully effective and efficient for all classes of work for which such machine may be employed.

75 It will be further apparent that by means

of my invention flanges may be turned in small reentrant openings, reentrant apertures having small openings thereto, or apertures of small diameter located wholly within the area of sheet metal plates whether such plates are large or small.

It will be further apparent that the forming edge of the annular forming element may be adjusted for optimum operative position for various kinds or thicknesses of material and to compensate for wear thereof, and that, further, the forming element being of substantially uniform cross-section and substantially encircling one of the rolls ensures longevity for the element.

It will be noted, further, that the housing 1 and cover 2 enclose all of the gearing and shafts except the extremities thereof and that the workman using the device is thus protected from accidental injury.

While I have shown and described, by way of example only, one embodiment of my invention, it will be apparent that various changes may be made therein without departing from the intended scope and spirit of the invention. I do not therefore desire to limit myself to the foregoing except as may be pointed out in the appended claims.

Having thus completely described my invention, what I claim as new and original and desire to secure by United States Letters Patent is:

1. An edge-turning machine comprising, a hollow shaft having a gear and roll thereon, a stub shaft having a gear in mesh with the gear on said hollow shaft and a roll adjacent to said first roll, a housing for said shafts and gears, a support rod extending through said hollow shaft, rigidly secured to said housing and extending therethrough, a work table adjustably secured to the extended portion of said support rod, said rod being the sole supporting means between said housing and said work table, means associated with one of said rolls for imparting rotary motion thereto to draw a sheet of metal between said rolls and said work table so that a portion thereof passes between said rolls, a forming element having an extremity thereof operatively positioned between the periphery of said rolls for cooperating with said rolls to turn the edge of the metal passing therebetween substantially at right angles with the plane of the balance of the sheet of metal.

2. An edge-turning machine comprising, a hollow shaft having a gear and roll thereon, a stub shaft having a gear in mesh with the gear on said hollow shaft and a roll adjacent to said first roll, a housing for said shafts and gears, a support rod extending through said hollow shaft, rigidly secured to said housing and extending therethrough, a work table adjustably secured to the extended portion of said support rod, means associated with one of said rolls for imparting rotary motion thereto to draw a sheet of metal between said rolls and said work table so that a portion thereof passes between said rolls, a forming element of substantially uniform cross-section substantially encircling one of said rolls and having an extremity thereof positioned operatively between the periphery of said roll for cooperating with said roll to turn the edge of the metal passing therebetween substantially at right angles with the plane of the balance of the sheet of metal.

3. An edge-turning machine comprising, a hollow driving shaft having a gear and roll

thereon, a stub shaft having a gear in mesh with the gear on said driving shaft and a roll adjacent said first mentioned roll, a housing for said shafts and gears, a supporting rod extending through said hollow driving shaft, rigidly secured to said housing and extending therethrough, a work table adjustably secured to the extension of said supporting rod, means associated with one of said rolls for imparting rotary motion thereto to draw a sheet of metal between said rolls and said work table so that a portion thereof passes between said rolls, an annular forming element substantially encircling one of said rolls and being rotatable around said roll whereby the forming edge thereof may be adjusted with respect to the periphery of said rolls for optimum operative position and to compensate for wear of said element and said forming edge cooperating with said rolls to turn the edge 20 of the metal passing therebetween substantially at right angles to the plane of the balance of the sheet.

4. An edge-turning machine comprising, a hollow driving shaft having a gear and roll carried thereon, a stub shaft having a gear in mesh with the gear on said driving shaft and a roll adjacent said first mentioned roll, a housing for said shafts and gears, a support rod extending through said hollow driving shaft, rigidly secured to said housing and extending therethrough, a work table adjustably secured to said support rod, means associated with one of said rolls for imparting rotary motion thereto to draw a sheet of metal between said rolls and said 35 work table so that a portion thereof passes be-

tween said rolls, a forming element substantially encircling one of said rolls and carried by said work table and rotatable with said work table about said support rod to permit adjustment of the forming edge thereof with respect to the peripheries of said rolls to compensate for wear of said edge, said forming edge cooperating with said rolls to turn the edge of the metal passing therebetween substantially at right angles with the plane of the balance of the sheet of metal.

5. An edge-turning machine comprising, a hollow driving shaft having a spur gear and a roll carried thereon, a stub shaft having a spur gear in mesh with the spur gear on said driving shaft and a roll adjacent to said first mentioned roll, a housing for said shafts and gears, means for moving one of said shafts to adjust the distance between the rolls carried by said shafts, a support rod extending through said hollow driving shaft, rigidly secured to said housing and extending therethrough, a work table adjustably secured to said support rod, means associated with one of said shafts and rolls for imparting rotary motion thereto through reducing gears to draw a sheet of metal between said rolls and said work table so that a portion thereof passes between said rolls, an annular forming element substantially encircling one of said rolls and having an extremity thereof operatively positioned between the peripheries of said rolls for cooperating with said rolls to turn the edge of the metal passing therebetween substantially at right angles to the plane of the balance of the sheet of metal.
